BOAT LADDER

Richard M. Wallace and John O. Young, Binghamton, N. Y., assignors to Lignacraft, Binghamton, N. Y., a partnership

Application June 17, 1954, Serial No. 31,027

Term of patent 14 years

(Cl. D15—1)

The figure is a perspective view of a boat ladder showing my new design.

The dotted line showings in the figure are for illustrative purposes.

We claim:

The ornamental design for a boat ladder, as shown and described.
